CLAIM

The ornamental design for a “basketball bank,” as shown and described.

DESCRIPTION

FIG. 1 is a front elevational view of a basketball bank showing my new design;

FIG. 2 is a rear elevational view of the basketball bank of FIG. 1;

FIG. 3 is a bottom plan view of the basketball bank of FIG. 1;

FIG. 4 is a top plan view of the basketball bank of FIG. 1; and,

FIG. 5 is a right side elevational view thereof, the opposite side is a mirror image.
